HIS ATTORNEY.

UNITED STATES PATENT OFFICE

ANTON N. LARSEN, OF WAUCONDA, ILLINOIS

SMOKER'S PIPE

Application filed February 2, 1931. Serial No. 512,954.

This invention relates to certain novel improvements in smoker's pipe, and has for its principal object the provision of an improved construction of this character which will be highly efficient in use and economical in manufacture.

It is among the several objects of this invention to provide a smoker's pipe which will enhance the pleasure of smoking and to construct the pipe in such a manner that the cleaning thereof will be facilitated.

Another object of the invention is to provide a member carried by the mouth piece and insertable into the stem and in which a passage is provided for conducting the smoke from the stem to the mouth piece, said member carrying a finger which is normally disposed in a recess provided in the bowl below the throat leading from the bowl to the stem and said member being rotatable, upon retraction thereof and withdrawal of said finger from said recess, whereby to insert said finger into said throat to clean accumulated tobacco and foreign matter therefrom.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a perspective view of a preferred form of construction of the invention, assembled for use;

Fig. 2 is a longitudinal sectional detail view of the invention as seen in Fig. 1, depicting the construction of the invention;

Fig. 3 is a sectional view on the line 3—3 in Fig. 2, and partly in elevation; and

Fig. 4 is perspective view of the member embodied in the invention and which member is shown in installed position in Fig. 2.

Referring to the drawings wherein a preferred form of construction of the invention is illustrated, the present invention provides a bowl 10 which is integral with a hollow stem 11 that has detachably mounted thereon a mouth piece 12. Leading from the bowl 10 to the interior passage 13 of the stem 11

is a throat 14 below which a recess 15 is formed in the bowl. A neck 16 is formed on the mouthpiece 12 and is insertable into the rear end of the passage 13. Carried by the neck 16 of the mouthpiece is a tubular member 17, the rear end portion 18 of which is disposed in the neck 16 (Fig. 2) and this union may be either integral or detachable. At the front end of the member 17 is formed a finger 22 which has a pointed front end 23.

A passage 20 is formed in the member 17 at the rear thereof, and this passage communicates at its rear end with the passage 19 in the mouthpiece while at its front end the passage 20 leads by a passage 21 to the interior 13 of the stem 11.

In use, the parts are disposed as in Fig. 2, and smoke will pass from the bowl 10, through throat 14, stem interior 13, and passages 21 and 20 to the passage 19 in the mouthpiece 12. Should the throat 14 become clogged with tobacco or other foreign matter, the finger 22 may be withdrawn from the recess 15, by gripping the mouthpiece 12 and withdrawing the same rearwardly, and then by rotating the member 17 a half revolution the finger 22 may be aligned with the throat 14 and inserted thereinto by pushing forwardly on the mouthpiece 12, so that any foreign matter clogging the throat 14 may be dislodged therefrom.

By reason of the position of the passage 21, foreign matter is prevented from entering the passage 20 and the mouthpiece passage 19 since any foreign matter passing through the throat 14 will collect in the stem interior 13 and thereby the pleasure of smoking will be enhanced.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention what

I claim as new and desire to protect by Letters Patent is:

1. In a smoker's pipe including a stem and a bowl having a throat leading from the bowl to the stem and having a recess therein below said throat, a mouthpiece, and a member carried by the mouthpiece having a passage therein communicating with the mouthpiece and said throat and including a finger normally disposed in said recess but insertable into said throat to dislodge foreign matter therefrom.
2. In a smoker's pipe, a bowl and a stem, said bowl having a throat therein leading into said stem and having a recess formed therein below said throat, and a mouthpiece detachable from said stem, a member carried by the mouthpiece, insertable into the stem and having a passage therein communicating with the interior of the stem, and a finger at the forward end of said member normally disposed in said recess but insertable into said throat to dislodge foreign matter therefrom by retracting said mouthpiece, giving the same a half revolution to align said finger with said throat, and moving said mouthpiece forwardly to position said finger in said throat.

In testimony whereof I affix my signature.

ANTON N. LARSEN.
